UNITED STATES PATENT OFFICE.

ERNEST E. WESSON, OF BLAIR STATION, PENNSYLVANIA, ASSIGNOR OF ONE-SIXTH TO ABRAHAM H. JOHNSON, OF BLAIR STATION, PENNSYLVANIA, ONE-SIXTH TO FLEMING H. JACKSON, AND ONE-SIXTH TO ROY L. GISSENDANNER, BOTH OF CLAIRTON, PENNSYLVANIA.

CHECK-OPERATED RADIO RECEIVING SET.

Application filed April 23, 1925. Serial No. 25,285.

To all whom it may concern:

Be it known that I, ERNEST E. WESSON, a citizen of the United States, residing at Blair Station, in the county of Allegheny 5 and State of Pennsylvania, have invented certain new and useful Improvements in Check-Operated Radio Receiving Sets, of which the following is a specification, reference being had to the accompanying 10 drawings.

This invention relates to radio receiving sets and more particularly to a check controlled receiving set.

An important object of the invention is 15 to provide in a device of this character a check controlled apparatus completing the circuit of a radio receiving set and rendering the same operative.

A further object of the invention is the 20 provision of a device of this character in which the radio receiving set includes multiple stages and in which the circuits of all stages are open until the proper check is inserted.

25 A still further object of the invention is to provide a device of this character having time controlled means for releasing the check to thereby reopen the circuit of the receiving set.

30 A still further object of the invention is the provision of a device of this character in which the check controlled apparatus is capable of simultaneously receiving a plurality of checks and has means for indicating when the last of these checks is being employed.

35 A further object of the invention is to provide in a device of this character means whereby the receiving set may be operated 40 at the option of the owner without the use of checks.

These and other objects I attain by the construction shown in the accompanying drawings, wherein for the purpose of illustration is shown a preferred embodiment 45 of my invention and wherein:—

Figure 1 is a perspective view of a check operated radio receiving set constructed in accordance with my invention;

50 Figure 2 is a sectional view taken through the check chute and the associated mechanism;

Figure 3 is a face view of the annulus applied to the clock;

Figure 4 is a detailed sectional view showing the manner of mounting the conductors upon the annulus; 55

Figure 5 is a second sectional view through the check chute showing in solid lines the positions occupied by the parts 60 when there are a plurality of checks within the chute and in dotted lines the position of the parts when there are no checks present in the check chute;

Figure 6 is a detailed sectional view showing the connector for completing the circuits of the audion bulbs; 65

Figure 7 is a detailed sectional view through the check chute showing the check stop in elevation; and 70

Figure 8 is a diagrammatic view showing the diagram of the receiving set proper and the check operated and time controlled apparatus. 75

Referring now more particularly to the drawings and more particularly to the diagrammatic view of Figure 8, the circuit disclosed in this diagrammatic view with the exception of that portion lying to the left of line A of the diagram may be the usual radio receiving circuit of any desired character. The present disclosure is of the well known standard type of a commercially produced receiving set. The receiving set 80 employed preferably employs at least two stages, a detector and one stage of amplification and each stage is open circuited.

In the present instance, this is accomplished by providing separate filament batteries 10 and 11 for the detector audion 90 12, and amplifier 13 employed in the set. One side of each of the batteries 10 and 11 is connected directly to the filament F of the audion. The opposite side of the battery 10 is connected to a loop connection including wires 14 and 15 of which the wire 15 is connected to the battery. This connection is open at two points, one of which is closable by a manually operable switch 16 and at the other of which the wires 14 and 15 95 have secured thereto spaced contacts 14^a, 15^a. The wire 15 is connected to the opposite terminal of the filament F in the usual manner and is isolated from the battery by the gaps at the switch and at the contacts 14^a, 15^a. 100 Similarly the opposite terminal of the battery 11 has connected thereto a loop connection including wires 17, 18, the connec-

tion being open at two points, one of which is closable by a switch 19 and at the other of which the ends of the wires 17 and 18 have secured thereto spaced adjacent contacts 17^a, 18^a. A signal lamp 20 is provided, one terminal of which is connected by a wire 21 with the side of the filament battery of the audion of the first stage of the receiving set which is connected to the filament. This signal lamp and the means for completing the circuit thereof will be hereinafter more fully explained.

The check controlled apparatus includes a chute 22, which chute is preferably in the form of a flat chute of a size to accommodate the checks to be employed, the closed walls of the chute at the lower end thereof being correspondingly notched, as at 23, leaving guides 24 to receive the edges of the check, generally designated at C. The notch of the upper wall is extended, as indicated at 25. The chute is arranged in an inclined position and above the upper end of the notch has secured there- to an insulating supporting post 26. To this supporting post 26 is pivoted an arm 27 which is electrically connected by a wire 28 with the second terminal of the signal lamp 20. The lower end of this arm is directed into the notch 25 and is of greater weight than the upper end thereof so that it normally rests against the bottom of this chute.

When this is the case, its upper end comes into engagement with a stationary contact 29 carried by the chute 22 and electrically connected through a manually operable switch 30 with the wire 15. This wire as will be noted from an inspection of the loop circuit is out of circuit with the battery 10 until the loop circuit is completed, either by the switch 16 or by bridging of the contacts 14^a, 15^a. When this circuit is completed through the switch 16, the switch 30 will be opened as at this time operation of the set without the use of checks is contemplated. When the circuit is completed through the wire 14 and the switch 30 is closed, the circuit of the lamp 20 is completed and this lamp, which is arranged at some conspicuous point on the outer wall or panel of the set, is energized if the lower end of the lever 27 is in engagement with the bottom of the chute, as described. If, however, a check be arranged between the lower end of this lever and the base 31 of the chute, the lever is disconnected from the contact 29 and the circuit of the lamp is broken. Since the check to be arranged beneath the end of the lever must be supported from a second check which is arranged at the lower end of the chute, as will be hereinafter more fully explained, energizing of the lamp occurs only when there is but one check in the machine and the machine is being check operated.

65 Pivoted to the lower end of the chute upon

brackets 32 carried by the guides 24 is an insulated lever 33. To the upper end of this lever are secured the contacts 14^a, 15^a, 17^a and 18^a. The connection between this lever and the wires 14, 15, 17 and 18 being accomplished through flexible terminals, as shown, so that the upper end of the lever is freely movable. Pivoted to the lower end of the lever between the pivot thereof and its lower extremity is an arm 34 having one end extending beneath the end of the chute and into the notch 23, this end being indicated at 35, and at its opposite end having secured hereto an insulating bar 36. This arm itself is of conducting material, for a purpose presently to appear.

While the end 35 of the arm 34 is positioned beneath the chute for the reception of checks passing downwardly through the chute, this only occurs in what may be termed the normal position of the lever 33 which is the position illustrated in Figure 8. While the lever is in this position and no check is within the chute, the end bearing the insulating strip 36 of the arm 34 is the heavier and this arm remains in the position shown in this figure. This insulating strip has resilient contacts 37 and 38. When a check is within the chute and engaged against the end 35 of the arm, the arm is overbalanced and these bridging contacts 37 and 38 are moved into engagement with the pairs of contacts 14^a and 15^a respectively to close the circuits thereof. At the same time, the end 35 of the arm in its downward movement under the influence of the inserted check comes into engagement with a contact 39. A spring 40 normally maintains the lever 33 in position.

Arranged adjacent the lower end of the lever is an electro-magnet 41, the armature 42 of which is connected with the lower end of the lever 33 by a link 43. One terminal of the electro-magnet is connected with one terminal of a battery 44 by a wire 45. The opposite terminal is connected by a wire 46 to a terminal 47 of a connection bar 48. This terminal is connected with the end 35 of the arm 34 by a flexible lead 49. The contact 39 is connected by a flexible lead 50 to a second binding post of the arm 48 and from this binding post a wire 51 is led. A timing apparatus which may be of any suitable character is generally designated at 52 and includes a rotating brush 53 operating from the minute hand of a clock and associated with an annulus 54. This annulus is divided into spaces corresponding to five minute intervals and has arranged therebeneath a pair of leads 55 and 56, each lead being brought to the upper surface of the annulus 54 at intervals corresponding to the five minute interval and there having its insulation removed. The leads are in parallel relation and the brush 53 is of sufficient

size to bridge the two leads. One of these leads is connected to the wire 51 while the other is connected with a wire 57 leading to the second terminal battery 44.

5 It will be obvious that if a check is in engagement with the arm 34 and accordingly the end 35 of this arm engaged with the contact 39, a circuit will be established through the electro-magnet by the clock mechanism, at five minute intervals. When the electro-magnet is energized, the lever 33 is moved to the position shown in Figure 2 so that the arm end 35 is withdrawn from beneath the check, permitting the same to fall into a receptacle 58. When the weight of the check is removed from the arm 35, this arm does not rotate about its pivot for the reason that when the lever is in the position shown in Figure 2, the upper end of 10 the arm 35 is overbalanced and accordingly the circuits of the loop connections 14, 15, 17 and 18 are not broken. When positioned through the electro-magnet, the lever has an arm 59 projecting into the upper end 15 of the notch 23 and into the path of checks following the check which is to be released, thus preventing more than one check from passing from the chute during such momentary operation. When the lever is in its 20 normal position, this arm is out of the path of the check. Accordingly, when the brush of the clock work mechanism is shifted sufficiently to open the circuit of the electro-magnet and permit the lever 33 to be 25 turned to its normal position by the spring 40, a check will be released and will engage the arm 35 to maintain the circuit of the loop connections 14, 15, 17 and 18. If, on the contrary, there is no check present in 30 the chute, this arm will move to its open position and will open these circuits.

The complete operation of the device is as follows:— If the device is to be employed merely as a radio set without the use of 45 checks, the switches 16 and 19 are closed and the switch 30 open. This will allow operation of the set and will prevent any operation of the signal light 20. The operating dials 60 of the set have arranged adjacent 50 the same indicators 61 showing the positions of these operating dials for any given station so that the desired station may be selected before the set is placed in operation. When operating a set by means of checks, these dials are first properly positioned and the phones or loud speaker connected at the 55 stage through which it is desired that the station selected be heard. The proper check or series of these checks is then inserted. 60 The first check engaging the arm 34 will complete the circuit of this arm with the contact 39 and of the time control mechanism with the exception of the clock switch. At 65 the same time, the weight of the check will cause completion of the loop circuits 14, 15,

17 and 18 and ignite the filaments of the audions 12 and 13. If but a single check is inserted, it will at the same time cause the lamp 20 to be energized while if a plurality of checks have been entered, this lamp will 70 be inoperative. If the proper adjustments have been made, the station should be heard immediately upon insertion of the check. Assuming that a plurality of checks have been entered at five minute intervals, one 75 check will be withdrawn at a time until but a single check remains in the slot. When this occurs, the lamp 20 is energized, warning that the five minute interval starting is the last paid for by the checks. As the last 80 check leaves the machine, the circuit of the loop circuits 14, 15, 17 and 18 are broken and the filaments of the audions extinguished.

It will be obvious that while the filament circuit of the audion has been selected as the proper point for breaking the circuits of these audions, this may be accomplished in another manner if this is found desirable. It will also be obvious that the structure of the check control mechanism is capable of a certain range of change and modification without materially departing from the spirit of my invention and I accordingly do not limit myself to such specific structure except as hereinafter claimed.

I claim:—

1. In combination with a radio receiving circuit including an audion bulb, an open filament-lighting circuit for the bulb and check controlled means for closing the filament circuit, including a check chute for the simultaneous reception of a plurality of checks, a signal element and means for rendering the signal element operative when the filament circuit of the audion is closed and but a single check remains in the check chute.

2. In combination with a radio receiving circuit including an audion bulb, an open filament-lighting circuit for the bulb, check controlled means for closing the filament circuit, including a check chute for the simultaneous reception of a plurality of checks, a signal element and means for rendering the signal element operative when the filament circuit of the audion is closed and but a single check remains in the check chute, including a circuit for the signal open at two points, one of which is closed by closing of the filament circuit and the other of which embodies a stationary and a movable contact, the movable contact being pivoted intermediate its ends and having one end opposed to one wall of the chute and normally engaging therewith, said arm, when said end thereof is in engagement with the wall of the chute, having the opposite end thereof in engagement with the stationary contact to complete the circuit, the

- first named end of said arm being positioned with relation to said chute to be separated therefrom by the check next above that check causing closing of the filament circuit.
5. In combination with a radio receiving circuit including an audion bulb, an open filament-lighting circuit for the bulb and check controlled means for closing the filament circuit including a check chute, a pivoted member having one arm thereof disposed beneath the check chute to receive a check passing therethrough, an insulating bar to which said arm is pivoted and having spaced contacts connected at opposite sides 70 of the opening of the filament lighting circuit and a bridging contact carried by said pivoted arm and moved into engagement with the spaced contacts when the check engages the arm, a stationary contact 75 arranged beneath said arm, a time operated circuit closer having contacts closed at predetermined intervals, a source of energy and an electro-magnet with which one terminal of the source of energy is connected, the 80 opposite terminal of the source of energy being connected with the last named contact through the time operated circuit closer, a connection between the second terminal of the electro-magnet and said bar whereby a 85 check engaging with the arm completes the circuit of said electro-magnet with the exception of the contacts on said time operated circuit closer and a connection between the armature of the electro-magnet and the support of said arm for shifting said support 90 and arm to permit release of the check when the circuit is completed through said time controlled apparatus.
4. In combination with a radio receiving circuit including an audion bulb having an open filament-lighting circuit, an electrical signal connected across the terminals of the audion, check controlled means for completing the filament circuit of the audion and means for opening the circuit of the signal when there is more than one check present in the check controlled means.
5. In combination with a radio receiving circuit including an audion bulb having an open filament-lighting circuit, an electrical signal connected across the terminals of the audion, check controlled means for completing the filament circuit of the audion and means for opening the circuit of the signal when there is more than one check present in the check controlled means including a switch having a pivoted arm arranged in the path of checks passing to the check controlled apparatus and positioned to be engaged by the check next above that check engaged with the check controlled apparatus, said arm when engaged with a check being shifted to open the circuit.
6. In combination with a radio receiving circuit including an audion bulb having an open filament-lighting circuit, an electrical signal connected across the terminals of the audion check controlled means for completing the filament circuit of the audion, means for opening the circuit of the signal when there is more than one check present in the check controlled means, manually controllable means for closing the circuit of the filament of the audion and manually controllable means for opening the circuit of the signal.
7. In combination with a radio receiving circuit including an audion bulb, an open filament-lighting circuit for the bulb, an electrically operable signal connected across the filament terminals of the bulb and having in series therewith a switch, check operated mechanism for closing the circuit of the filament, including a pivoted switch and a chute for delivering checks to the switch, the first named switch having an arm normally overlying the under side of the check chute at the point occupied by the check next above that engaged with said pivoted switch, in which normal position of said arm the terminals of the first named switch are engaged, said arm being spaced from the under wall of the check chute a distance less than the thickness of a check 95 whereby the first named switch is opened and the signal rendered inoperative by the next to the bottom check engaging said arm when there are a plurality of checks within the check chute, said signal also being rendered inoperative by the opening of the filament circuit when there is no check present in the check chute.
8. In combination with a radio receiving circuit including an audion bulb, an open filament-lighting circuit for the bulb, an electrically operable signal connected across the filament terminals of the bulb and having in series therewith a switch, check operated mechanism for closing the circuit of the filament, including a pivoted switch, a chute for delivering checks to the switch, the first named switch having an arm normally overlying the under side of the check chute at the point occupied by the check next above that engaged with said pivoted switch, in which normal position of said arm the terminals of the first named switch are engaged, said arm being spaced from the under wall of the check chute a 100 distance less than the thickness of a check whereby the first named switch is opened and the signal rendered inoperative by the next to the bottom check engaging said arm when there are a plurality of checks within the check chute, said signal also being rendered inoperative by the opening of the filament circuit when there is no check present in the check chute.
9. In combination with a radio receiving circuit including an audion bulb having an open filament-lighting circuit, an electrical signal connected across the terminals of the audion, check controlled means for completing the filament circuit of the audion and means for opening the circuit of the signal when there is more than one check present in the check controlled means including a switch having a pivoted arm arranged in the path of checks passing to the check controlled apparatus and positioned to be engaged by the check next above that check engaged with the check controlled apparatus, said arm when engaged with a check being shifted to open the circuit.
10. In combination with a radio receiving circuit including an audion bulb having an open filament-lighting circuit, an electrical signal connected across the terminals of the audion, check controlled means for completing the filament circuit of the audion and means for opening the circuit of the signal when there is more than one check present in the check controlled means, manually controllable means for closing the circuit of the filament of the audion and manually controllable means for opening the circuit of the signal.

9. In combination with a radio receiving circuit including an audion bulb, an open filament-lighting circuit for the bulb, an electrically operable signal connected across the filament terminals of the bulb and having in series therewith a switch, check operated mechanism for closing the circuit of the filament, including a pivoted switch, a chute for delivering checks to the switch, the first named switch having an arm normally overlying the under side of the check chute at the point occupied by the check next above that engaged with said pivoted switch, in which normal position of said arm the terminals of the first named switch are engaged, said arm being spaced from the under wall of the check chute a distance less than the thickness of a check whereby the first named switch is opened and the signal rendered inoperative by the next to the bottom check engaging said arm when there are a plurality of checks within the check chute, said signal also being rendered inoperative by the opening of the filament circuit when there is no check present in the check chute and time controlled means rendered operative by the insertion of a check releasing the check when the pivoted switch has been in closed position through a predetermined interval.
10. In combination with a radio receiving circuit including an audion bulb, an open filament-lighting circuit for the bulb, an electrically operable signal connected across the filament terminals of the bulb and having in series therewith a switch, check operated mechanism for closing the circuit of the filament, including a pivoted switch and a chute for delivering checks to the switch, the first named switch having an arm normally overlying the underside of the check chute at the point occupied by the check next above that engaged with said pivoted switch, in which normal position of said arm the terminals of the first named switch are engaged, said arm being spaced from the under wall of the check chute a distance less than the thickness of a check whereby the first named switch is opened and the signal rendered inoperative by the next to the bottom check engaging said arm when there are a plurality of checks within the check chute, said signal also being rendered inoperative by the opening of the filament circuit when there is no check present in the check chute, time controlled means for releasing or for engaging the last named switch after a predetermined period of engagement and means for maintaining the check engaged by the first named switch against movement during operation of the time controlled means and until the last named switch is restored to its check receiving position.
11. In combination with a radio receiving circuit including an audion bulb, an open filament-lighting circuit for the bulb, an electrically operable signal connected across the filament terminals of the bulb and having in series therewith a switch, check operated mechanism for closing the circuit of the filament, including a pivoted switch and a chute for delivering checks to the switch, the first named switch having an arm normally overlying the under side of the check chute at the point occupied by the check next above that engaged with said pivoted switch, in which normal position of said arm the terminals of the first named switch are engaged, said arm being spaced from the under wall of the check chute a distance less than the thickness of a check whereby the first named switch is opened and the signal rendered inoperative by the next to the bottom check engaging said arm when there are a plurality of checks within the check chute, said signal also being rendered inoperative by the opening of the filament circuit when there is no check present in the check chute, time controlled means rendered operative by the insertion of a check releasing the check when the pivoted switch has been in the closed position through a predetermined interval and means for maintaining the remaining checks against movement during the release of the switch engaged check.
12. In combination with a radio receiving circuit including an audion bulb, an open filament-lighting circuit for the bulb, an electrically operable signal connected across the filament terminals of the bulb and having in series therewith a switch, check operated mechanism for closing the circuit of the filament, including a pivoted switch and a chute for delivering checks to the switch, the first named switch having an arm normally overlying the under side of the check chute at the point occupied by the check next above that engaged with said pivoted switch, in which normal position of said arm the terminals of the first named switch are engaged, said arm being spaced from the under wall of the check chute a distance less than the thickness of a check whereby the first named switch is opened and the signal rendered inoperative by the next to the bottom check engaging said arm when there are a plurality of checks within the check chute, said signal also being rendered inoperative by the opening of the filament circuit when there is no check present in the check chute, time controlled means rendered operative by the insertion of a check releasing the check when the pivoted switch has been in the closed position through a predetermined interval and means for maintaining the remaining checks against movement during the release of the switch engaged check.

In testimony whereof I hereunto affix my 125
signature.

ERNEST E. WESSON.
